UNITED STATES PATENT OFFICE.

WILLIAM MAGNER, OF LOCKPORT, NEW YORK.

TROLLEY-STAND.

SPECIFICATION forming part of Letters Patent No. 729,620, dated June 2, 1903.

Application filed November 6, 1902, Serial No. 130,334. (No model.)

To all whom it may concern:

Be it known that I, WILLIAM MAGNER, a citizen of the United States, residing at Lockport, in the county of Niagara and State of New York, have invented new and useful Improvements in Trolley-Stands, of which the following is a specification.

This invention relates to trolley-stands which are designed more especially for comparatively long cars of the kind used on suburban lines and which can be shifted near either end of the car to enable the conductor to conveniently replace the trolley upon the conducting wire from the rear platform, which operation is awkward and attended with more or less danger when the trolley-stand is permanently located in the center of such a long car.

The principal object of my invention is to provide a stand of this class which combines the advantages of simplicity and cheapness of construction with a compact and sightly arrangement of the parts.

Further objects of the invention are to improve the construction of the trolley-carriage and its guide-rails with a view of insuring the easy running of the carriage and to provide improved locking devices for the carriage, which are protected from snow, ice, &c.

In the accompanying drawings, consisting of two sheets, Figure 1 is a side elevation of the upper portion of a car equipped with my improved trolley-stand. Fig. 2 is a top plan view thereof. Fig. 3 is a fragmentary longitudinal section of the trolley-stand and adjacent parts on an enlarged scale. Figs. 4 and 5 are horizontal sections in the correspondingly-numbered lines in Fig. 3. Fig. 6 is a transverse section in line 6 6, Fig. 3. Fig. 7 is a longitudinal section in line 7 7, Fig. 6.

Similar letters of reference indicate corresponding parts throughout the several views.

Upon the roof A of the car is arranged a longitudinal track consisting, preferably, of a rigid board or platform B, supported a short distance above the roof by cleats b and provided at its edges with longitudinal rails C C, extending throughout the length of the board. Each of these rails preferably has upper and lower horizontal webs c, which extend outwardly from the vertical body of the rail and which are provided at their

outer edges with substantially vertical lips or flanges c', which form the heads or wearing-surfaces of the rails. As shown in Fig. 6, 55 the upper lip of each rail is turned downwardly and the lower lip upwardly, and the two opposing lips are vertically in line with each other, forming a rail of approximately C-shaped cross-section. The rails may be 60 formed of sheet metal or malleable iron. They are preferably arranged to extend above and below the supporting-board B and secured to the latter by transverse bolts, which may extend across the entire width of the 65 board and pass through both rails, as shown in Figs. 4 and 6.

D indicates a truck or carriage running on the track-rails C and constituting a shiftable base for the trolley-pole E and its stand. 70 This carriage preferably consists of a horizontal body-plate d, somewhat wider than the distance between the track-rails C and provided at its longitudinal edges with depending flanges d', arranged on the outer sides of 75 the rails. On the inner sides of these flanges are arranged wheels or rollers d", which run between the opposing lips c' of the rails, the wheels having grooves which receive said lips, thereby keeping them in engagement with the 80 rails. The axles d³ of the wheels are supported at their outer ends in the carriage-flanges d' and at their inner ends in longitudinal bearing-bars f, secured to the adjacent sides of 85 said flanges and arranged between the upper and lower rail-webs c, as shown in Figs. 4 and 6. As shown in the last-mentioned figure, the webs c of the rails extend outwardly a sufficient distance from the vertical body portions thereof to insure ample clearance between the carriage-wheels and their bearings 90 and the body portions of the rails.

The trolley-stand is mounted upon the carriage D and preferably comprises an upright stud g, rising centrally from the horizontal top 95 of the carriage, and a hub or sleeve g', journaled thereon. The vertically-swinging trolley-pole, which may be of any suitable construction, has its bifurcated lower end pivoted to the hub g' and may be provided with 100 any suitable spring mechanism for pressing it against the trolley-wire. The pressure device shown in the drawings consists of a yoke H, pivoted at its front end to the lower portion

of the trolley-pole and guided on a horizontal rod h , extending forwardly from a bracket h' of the stand, a spring h^2 surrounding this rod between said bracket and the rear cross-bar 5 of the yoke.

It will be understood from the foregoing description that the trolley-pole can be reversed on the carriage D in the same manner as an ordinary pole is reversed on the usual fixed 10 stand and base.

Any suitable means may be employed for preventing displacement of the trolley-carriage after the same has been shifted to either end of its track; but I prefer to employ automatic locking devices which are released in 15 the act of reversing the trolley-pole. The locking devices shown in the drawings consist of a pair of vertically-swinging catches or levers I I, arranged lengthwise on the under 20 side of the top plate d of the carriage on opposite sides of the stud g . These catches are adapted to interlock, respectively, with cross-pieces or stops j , projecting from the upper side of the board A and arranged near opposite 25 ends thereof. Each catch is provided at its outer or front end with a head having a shoulder i , adapted to engage with its companion cross-piece j , and a beveled under face i' , which rides over the cross-piece and causes 30 its shoulder to automatically interlock with the same when the carriage is moved to the end of the track. The headed arms of the locking-catches are preferably longer or heavier than their inner arms, so as to remain 35 in engagement with the cross-pieces j by gravity. The inner arms of the catches are turned upwardly and extend through openings formed in the top plate of the carriage on the front and rear sides of the trolley-stand. 40 These upturned ends preferably carry anti-friction-rollers k , the journals of which are arranged at right angles to the pivots of the catches.

L indicates a releasing arm or plate secured 45 horizontally to the hub g' in line with the trolley-pole, but on the opposite side therefrom, and adapted to ride alternately over the rollers of the locking-catches I for depressing their inner arms and unlocking their shoulderered outer arms from the corresponding 50 cross-piece j . When the carriage is at either extremity of its track, that catch which for the time being is at the same side of the trolley-stand as the pole is clear of the releasing- 55 arm L, which latter is on the opposite side of the stand, allowing said catch to remain interlocked with its companion cross-piece j , as shown in Fig. 3. At the same time the other catch is held in its elevated position by bearing 60 with its inner arm against the under side of the overlying releasing-arm. When it is desired to shift the trolley-pole to the opposite end of the car, the pole is simply reversed. As the releasing-arm L is carried by the hub 65 g' it takes part in the half-turn of the hub, riding over the roller of the locked catch and releasing the same from the adjacent cross-

piece j , thereby unlocking the carriage and permitting it to be drawn to the other end of the track by means of the trolley-pole and the controlling-rope depending from it. By being thus turned to the opposite side of the trolley-stand the releasing-arm clears the other elevated catch, allowing its shouldered head to drop by gravity into a position in 70 which it encounters the cross-piece j at the other end of the track and automatically interlock therewith as soon as the carriage is shifted to that end of the track. As the catches are located on the under side of the carriage and between the depending side flanges of the same, they are covered and not liable to become clogged with snow and ice. 75

To prevent the carriage from running beyond the ends of the rails, suitable stop-bars m are secured across the ends of the rails and the supporting-board B. 80

By my improved construction of the carriage and the rails the carriage while being reliably held in engagement and in contact 90 with the rails cannot become bound, insuring its easy running at all times, and by extending the sides or flanges of the carriage down over the outer sides of the wheels snow and ice are excluded from the latter. The parts 95 constituting the trolley stand and base are, moreover, few in number and compact in arrangement and do not project to an objectionable extent above the car-roof, producing an inexpensive construction which is at the same 100 time sightly in appearance.

The stud or pivot g of the trolley-stand is preferably made removable, so that it may be interchanged with the stud of another type of stand, permitting different styles of stands 105 to be mounted on the same carriage D. For this purpose the stud may be secured in place by an ordinary clamping nut n , applied to its screw-threaded lower end and bearing against the under side of the carriage-top, as 110 shown in Fig. 3.

I prefer to make the track-rails C in separate insulated sections, as shown in the drawings, and to connect the motor-circuit of the car with the end sections C' only, as shown 115 in Fig. 1. These end sections may be included in the motor and controller circuit in any suitable manner; but each end section is preferably connected by a wire o with the controller P at the opposite end of the car. 120 By this arrangement when the motor-circuit is closed by either controller the current flows from the trolley-pole through the carriage D, the adjacent live track section C', wire o , the controller P, at the opposite or advancing end of the car, and the motor, the other end section and the intermediate section of the carriage-track and the other controller being cut out. This renders it impossible 125 for the motorman to operate the car by means of the other controller until after the conductor has reversed the trolley-pole and shifted it to the opposite end of the car, thereby guarding against injury to the trolley- 130

pole. This construction also reduces the liability of injury to repairmen, inasmuch as the greater portion of the track remains dead. If desired, the trolley-pole carriage may be shifted upon the dead middle section of the track in making repairs.

I claim as my invention—

1. The combination of a car-roof, and a track mounted thereon and comprising a pair of longitudinal rails, each of said rails consisting of an upright body portion, lower and upper webs extending outwardly from said body portion and vertical flanges extending upwardly and downwardly from said webs, substantially as set forth.

2. The combination of a car-roof, a track mounted thereon and comprising a pair of longitudinal rails, each consisting of an upright body portion, lower and upper webs extending outwardly from said body portion and vertical flanges extending upwardly and downwardly from said webs, respectively, a carriage having grooved wheels which engage with the vertical flanges of said rails, and a trolley-pole mounted on said carriage, substantially as set forth.

3. The combination of a car-roof, a pair of rails arranged lengthwise thereon, each of said rails comprising an upright body portion, lower and upper webs extending outwardly therefrom and vertical flanges extending upwardly and downwardly from said webs, respectively, a carriage having depending side flanges, bearing-bars secured to the inner sides of said side flanges between the upper and lower webs of the rails and wheels journaled between said side flanges and bearing-bars and running on said tracks, and a trolley-pole mounted on said carriage, substantially as set forth.

4. The combination of a car-roof, a track arranged lengthwise thereon, a carriage running on said track and provided with locking devices for retaining it in position near either end of the track, a reversible trolley-pole mounted on the carriage, and a releasing device operated by the reversal of the trolley-pole and acting upon said locking devices, substantially as set forth.

5. The combination of a car-roof, a track arranged lengthwise thereon, a carriage running on said track and provided with locking-catches adapted to retain the carriage near either end of the track, a rotary trolley-stand mounted on the carriage and carrying a releasing device arranged to engage either of said locking-catches, substantially as set forth.

6. The combination of a car-roof, a track

arranged lengthwise thereon, a carriage running on said track and provided with vertically-swinging locking-levers arranged to face in opposite directions, and a rotary trolley-stand mounted on the carriage between said locking-levers and provided on one side thereof with a releasing-arm which is arranged to engage alternately with said locking-levers, substantially as set forth.

7. The combination of a car-roof, a track arranged lengthwise thereon, a carriage running on said track and provided on its underside with a pair of oppositely-facing locking-levers, the inner arms of said levers extending upwardly through openings in the top of the carriage, and a rotary trolley-stand mounted on the carriage between said levers and having a horizontal releasing-arm arranged to ride over the inner arms of said locking-levers for unlocking the same, substantially as set forth.

8. The combination of a car-roof, a track arranged lengthwise thereon, a carriage running on said track and provided on its underside with a pair of oppositely-facing locking-levers, the inner arms of said levers extending upwardly through openings in the top of the carriage, and carrying antifriction-rollers which are arranged crosswise of the carriage, a rotary trolley-stand mounted on the carriage between said locking-levers, a trolley-pole pivoted to one side of said stand, and a releasing-arm arranged on the opposite side of the stand and adapted to ride alternately over the rollers of said levers, substantially as set forth.

9. In a trolley-car, the combination of the car-roof, a metallic track arranged lengthwise thereon and having end sections which are insulated from the intermediate portion of the track and included in the motor-circuit, a carriage running on said track, and a trolley-pole mounted on said carriage, substantially as set forth.

10. In a trolley-car, the combination of the car-roof, a sectional metallic track arranged lengthwise thereon, controllers for the motor-circuit arranged at opposite ends of the car, means for electrically connecting each controller with a section of said track at the opposite end of the car, a carriage running on said track, and a trolley-pole mounted on said carriage, substantially as set forth.

Witness my hand this 4th day of November, 1902.

WILLIAM MAGNER.
